Primary Examiner — Brett Miller*Assistant Examiner* — Rani J Abdallah(74) *Attorney, Agent, or Firm* — Gerard J. McGowan, Jr.(57) **CLAIM**

The ornamental design for a bottle with pump, as shown and described.

DESCRIPTION

FIG. 1 is a perspective view from above and one side;

FIG. 2 is a front elevational view;

FIG. 3 is a rear elevational view;

FIG. 4 is a side elevational view;

FIG. 5 is an elevational view of the other side;

FIG. 6 is a top plan view; and,

FIG. 7 is a bottom plan view.

The broken lines in the figures illustrate portions of the bottle with pump that form no part of the claimed design.
